UNITED STATES PATENT OFFICE.

ISAAC CLAPPER, OF OSNABURG, OHIO.

EMBOSSING-MACHINE.

SPECIFICATION forming part of Letters Patent No. 699,149, dated May 6, 1902.

Application filed August 5, 1901. Serial No. 70,935. (No model.)

To all whom it may concern:

Be it known that I, ISAAC CLAPPER, a citizen of the United States, and a resident of Osnaburg, in the county of Stark and State of Ohio, have invented a new and Improved Embossing-Machine, of which the following is a full, clear, and exact description.

This invention relates to improvements in machines for embossing or imprinting ornamental designs on hollow building blocks or tiles during the process of forming the same; and the object is to provide a machine for this purpose of simple construction and in which the embossing-cylinder may be readily adjusted for a desired depth of impression.

I will describe an embossing-machine embodying my invention and then point out the novel features in the appended claims.

Reference is to be had to the accompanying drawings, forming a part of this specification, in which similar characters of reference indicate corresponding parts in all the figures.

Figure 1 is a front elevation of an embossing-machine embodying my invention. Fig. 2 is a side elevation thereof. Fig. 3 is a longitudinal section, and Fig. 4 is a side elevation showing a modified form of embossing-cylinder.

Referring to the drawings, 1 designates the mold-casing, within which is arranged the usual core 2, this core 2 at the inlet end of the mold being attached to a bar 3, connected to the rear end of the mold. The upper wall of the mold-casing is cut away, as indicated at 4, so that the embossing-cylinder may have its lower surface projected below the plane of the inner wall of the mold to engage against the clay forced through the mold.

Extended forward from opposite sides of the casing 1 at the top are brackets 5, between which the embossing-cylinder 6 rotates. The exterior of this cylinder 6 may have any desired pattern thereon, and it is held against the building-block by means of rollers 7, which engage against the inner surface of the cylinder. These rollers are mounted to rotate on studs 8, which are adjustable vertically in slots 9, formed in the brackets 5, and are held as adjusted by means of thumb-nuts 10. By making the rollers 7 adjustable the embossing-cylinder may be caused to

press more or less into the material, as desired.

In Fig. 4 I have shown the embossing-cylinder as consisting of two segmental sections 55 11 and 12, at the ends of which are inwardly-extended arms 13, mounted to rotate on a shaft 14, which is designed to have its bearings in standards 15 on the brackets 5. This shaft or rod 14 may be held at one end to engage against the outer side of one of the uprights 15, and at the other end it may be provided with a set-nut 16, so that the shaft will be held from upward movement as the sections of the cylinder rotate. 65

In operation as the clay is forced through the mold in the ordinary manner its movement will cause a rotary movement of the embossing-cylinder, so that the pattern on the cylinder will be transferred to the block. 70

While I have shown an embossing-cylinder for operating upon only one side of the block, it is obvious that embossing-cylinders may be arranged at the sides, or, in fact, embossing-cylinders may be employed for operating on 75 the several sides of the block.

An embossing device embodying my invention may be readily applied to block-forming machines of the ordinary construction, and as the cylinder is quite large it will require 80 but very little power to operate it.

The object in making a cylinder in two parts, as shown in Fig. 4, is to provide for embossing blocks that have plain end margins, and each section will be of a length to 85 print the block.

To reduce friction to a minimum, I provide the adjustable bearing-rollers 17.

Having thus described my invention, I claim as new and desire to secure by Letters 90 Patent—

1. In a building-block-embossing machine, a die comprising a casing and a core, brackets extended forward from the casing, rollers supported by the brackets, and an embossing-cylinder engaging with its inner surface against said rollers, substantially as specified. 95

2. In a building-block-embossing machine, a die comprising a casing and a core, brackets extended forward from the casing at opposite 100 sides, rollers adjustable vertically in said brackets, and an embossing-cylinder having

its inner surface engaged by said rollers, substantially as specified.

3. In a building-block-embossing machine, the combination with a die comprising a casting and a core, of brackets projecting from the casing, an embossing-cylinder, bearing-rollers for the cylinder at the ends of the brackets, and rollers mounted in the brackets intermediate of their ends and traveling on the inner surface of the embossing-cylinder, as set forth.

4. In a building-block-embossing machine, brackets for supporting an embossing-cylinder

der said brackets being adapted to be secured to the machine and each provided with an inclined slot at each end, a vertical slot at its middle, and a standard also at its middle, as and for the purpose set forth. 15

In testimony whereof I have signed my name to this specification in the presence of 20 two subscribing witnesses.

ISAAC CLAPPER.

Witnesses:

JOHN KEIM,
GEORGE E. VIVLAND.
